UNITED STATES PATENT OFFICE

GEORGE W. FUNK, OF ELGIN, ILLINOIS

DESIGN FOR A HOT DISH PAD OR SIMILAR ARTICLE

Application filed November 23, 1932. Serial No. 46,139. Term of patent 7 years.

To all whom it may concern:

Be it known that I, GEORGE W. FUNK, a citizen of the United States, residing at Elgin, in the county of Kane, and State of Illinois, have invented a new, original, and ornamental Design for a Hot Dish Pad or Similar Article, of which the following is a specification, reference being had to the accompanying drawing, forming part thereof,

Figure 1 is a view in plan of the hot dish pad showing my new design;

Figure 2 is an edge view of the same.

I claim:

The ornamental design for a hot dish pad or similar article, as shown.

GEORGE W. FUNK.
